UNITED STATES PATENT OFFICE.

JAMES MARSDEN, OF WIGAN, ENGLAND.

DESIGN FOR A PATTERN-CHART FOR EMBROIDERY.

SPECIFICATION forming part of Design No. 29,653, dated November 8, 1898.

Application filed September 21, 1898. Serial No. 691,568. Term of patent 14 years.

To all whom it may concern:

Be it known that I, JAMES MARSDEN, a subject of the Queen of Great Britain, residing in Wigan, in the county of Lancaster, England, have invented and produced a new and original Design for a Pattern-Chart for Embroidery, of which the following is a specification, reference being had to the accompanying drawing, forming a part thereof.

16 The drawing is a plan view of a pattern-chart, showing my new design.

As shown in the drawing, the leading or material feature of my design consists of a spiral spray of leaves and flowers.

15 A is the spiral stem, from which branch the opposite leaves B, of conventional oblanceolate shape. The spiral petioles C branch from the stem A between the opposite leaves B and support similar leaves B', from which 26 branch the cluster of spiral petioles D, supporting conventional flowers E of bell shape.

F represents a partially-opened bud supported upon spiral petiole G, branching from the stem A, and H is an ellipsoidal bud in the cluster of flowers at the upper end of the design. 25

Having thus described my invention, what I claim as new therein, and desire to secure by Design Letters Patent, is—

The design for a pattern-chart for embroidery, substantially as herein shown and described. 30

In witness whereof I have hereunto signed my name, this 5th day of September, 1898, in the presence of two subscribing witnesses. 35

JAMES MARSDEN.
